United States Patent Office.

JOHN HYSLOP AND CHARLES E. PHILLIPS, OF ABINGTON, MASSACHUSETTS.

Letters Patent No. 66,349, dated July 2, 1867.

IMPROVED SIRUP-PITCHER.

The Schedule referred to in these Letters Patent and making part of the same.

TO ALL WHOM IT MAY CONCERN:

Be it known that we, JOHN HYSLOP and CHARLES E. PHILLIPS, of Abington, in the county of Plymouth, and State of Massachusetts, have invented new and useful improvements in Sirup-Pitchers, and that the following description, taken in connection with the accompanying drawings, hereinafter referred to, forms a full and exact specification of the same, wherein we have set forth the nature and principles of our said improvements, by which our invention may be distinguished from all others of a similar class, together with such parts as we claim and desire to have secured to us by Letters Patent.

The present invention relates to the cover or lid of the sirup-pitcher; and it consists principally in so constructing that portion of the lid or cover which covers the nose to the pitcher that it will enter the said nose, and thus, as it were, cut off the flow of liquid therefrom, consequently not only causing and forcing the liquid to flow back into the pitcher, but also serving to wipe off the liquid from the nose.

In the accompanying plate of drawings our improvements in sirup-pitchers are illustrated, the figure being a central vertical section through the top and cover to a sirup-pitcher.

A, in the drawings, represents the top to a sirup-pitcher, and B its lid or cover hinged or pivoted thereto at one end, and by its other fitting over the nose or spout C to the cap. D, a knob or thumb-piece attached to lid or cover B, and E a bent spring applied to cover or lid and to top A in a suitable manner, such as is shown in the drawings, to cause the cover to close or shut. F, a block of cork, or other suitable material, applied to cover or lid B at its end or portion which covers the nose to the top-piece A. This block projects from the under side of the cover, and when closed fits within the nose or spout where the liquid or sirup flows therefrom, and thus acting as a cut-off to such flow prevents its dripping, causing the liquid to flow back into the pitcher.

Having thus described our invention, we claim as new, and desire to secure by Letters Patent—

The block F applied to the lid or cover of a sirup-pitcher, substantially as and for the purpose described.

We also claim the spring E, or its equivalent, in combination with the cover or lid B, substantially as described for the purpose specified.

JOHN HYSLOP,
CHARLES E. PHILLIPS.
